UNITED STATES PATENT OFFICE.

CHARLES GRAFF, OF NEW YORK, N. Y., ASSIGNOR TO ROBERT C. BLACK AND AARON V. FROST, OF NEW YORK, N. Y., UNDER FIRM-NAME OF BLACK, STARR & FROST.

DESIGN FOR A CUP.

SPECIFICATION forming part of Design No. 35,785, dated March 4, 1902.

Application filed February 5, 1902. Serial No. 92,753. Term of patent 7 years.

To all whom it may concern:

Be it known that I, CHARLES GRAFF, of New York, county of New York, State of New York, have invented and produced a certain new and 5 original Design for a Cup, fully described and represented in the following specification and the accompanying drawing, forming a part of the same.

A cup embodying the design is shown in the 10 drawing, and the characteristic features of the design are the shape and configuration of the cup, with the body having the inward curve *a* below the rim *b* and then curving outward to form the swell *c*, having the bead *d*, and

then inward below the bead to the base *e*, and 15 being provided on opposite sides with the handles *f*, as shown.

What I claim is—

The design for a cup, substantially as shown and described. 20

In testimony whereof I have hereunto set my hand in the presence of two subscribing witnesses.

CHARLES GRAFF.
